UNITED STATES PATENT OFFICE.

BASILE SOLDATENCOW, OF PARIS, FRANCE.

PRINTING-TELEGRAPH.

1,034,405.

Specification of Letters Patent. Patented July 30, 1912.

Application filed February 5, 1912. Serial No. 675,400.

To all whom it may concern:

Be it known that I, BASILE SOLDATENCOW, of 37 Rue La Pérouse, Paris, France, have invented certain new and useful Improvements in and Relating to Printing-Telegraphs, of which the following is a specification.

The present invention relates to a printing telegraphic device, comprising an electro-magnetic device having two distinct actions and provided with a single solenoid by which means it is possible to obtain different and distinct effects. It is thereby possible to reduce the consumption of current, as well as the size and cost of the apparatus.

The accompanying drawings show by way of example a transmitting and receiving apparatus constructed according to the invention.

Figure 1 is a diagrammatic view of the electromagnetic device according to the invention. Figs. 2 to 4 illustrate an apparatus embodying the invention at different stages in its operation. Fig. 5 is a transverse section of a printing telegraphic instrument along line 1—1—1—1 of Fig. 7. Fig. 6 is a sectional side elevation along line 2—2 of Fig. 5. Fig. 7 is a section along line 3—3—3—3 of Fig. 5. Fig. 8 is a plan with part of the keyboard and its supporting plate removed. Figs. 9 to 13 show details. Figs. 14 and 14^a are diagrammatic views of the various connections. Figs. 15 to 18 show a device for setting transmitting and receiving apparatus in concordance.

The electro-magnetic device according to the invention consists (Fig. 1) of a solenoid A to which current is supplied by an electric circuit B (the source of current being at I). The circuit B is divided outside the solenoid and includes in one of the divisions C a switch or other device D which only permits such current to pass that the magnetic field generated shall be sufficient to produce a given attraction or magnetization of the core G. In the other division of the circuit E is inserted a switch or other device F which permits such current to pass that the magnetic field generated shall be sufficient to cause a stronger attraction or magnetization than the first, for the purpose of obtaining by means of a single solenoid and a single electric circuit different and distinct effects.

The apparatus acts as follows, supposing that the core G is attached to a fixed point J by means of a spring H whose tension is

suitably adjusted: When closing the switch D a magnetic field is produced in the solenoid which attracts the core G and tensions the spring H. If switch D is opened the magnetic field disappears and the spring contracts and pulls up the core G. Effects of the same kind are obtained with the switch F. If the current is only allowed to pass for a very short time, the magnetic field produced will be very weak. If, on the contrary, the period during which the current passes is longer the magnetic field will be more intense. It will therefore be seen that by suitably acting upon the two switches either simultaneously or successively, magnetic fields of different intensities can be produced, and the magnetic fields will cause a greater or smaller magnetization of the core G, resulting in a succession of reciprocatory movements of the said core in combination with the spring H simultaneously by the attraction or release of organs whose weight and position are determined according as the magnetic field created is sufficient or not to influence them.

In practice the arrangement shown in Figs. 2 to 4 can be used. A represents a solenoid or electro-magnet having a stationary core 80 and a movable core 81. One of the divisions of the electric circuit is constituted by wire 82, starting from the source of current 83 and having a suitable switch 84, a bracket 85 on which is pivoted at 86, a conducting lever 87 having a spring contact member 88, which latter can contact with a conducting lever 89 mounted in a conducting bracket 90 connected by wire 91 to the solenoid A which finally is connected to the source of current 83 by the wire 92. A non-conducting extension 93 of lever 89 is pivoted at its extremity to the movable core 81. The contact member 88 is mounted in a casing 94 which can be moved along the lever 87. The latter carries an insulating piece 95 placed between an adjustable abutment 96, mounted on the end of the lever 89, and a second adjustable stop 97. A counter-weight 98 whose position can be adjusted is mounted on the other end of lever 87 and returning springs 99 and 100 are fitted on levers 87 and 89 respectively.

The second division of the circuit is constituted by the wire 101 connecting the two points 102 and 103 of the circuit and including a switch 104.

In Fig. 2, the switch 104 is open (the usual

key 84 being depressed) and the circuit is the following: wire 82, bracket 85, lever 87, spring contact 88, lever 89, bracket 90, wire 91, the winding of the solenoid A and wire 92. The movable core is thereby attracted and together with lever 89, 93, takes up the position shown in Fig. 3. The stop 96 raises the insulating block 95 and swings the lever 87 and thereby removes contact 88 from lever 89 and interrupts the current. The core 81 is now no longer attracted and the springs 100 and 99 return the corresponding levers 89 and 87 into the positions shown in Fig. 2, thereby again closing the circuit, in that contact 88 makes contact with lever 89. By this means the core 81 is again attracted, which attraction again breaks the circuit, and this cycle of operations continues indefinitely. In this way a rapid pulsatory movement of the movable core 81 is obtained by the rapid succession of opening and closing of the contact making and breaking device 88-89.

If the switch 104 (Fig. 4) is closed the following circuit is formed: wire 82, branch 101, switch 104, wire 91, solenoid A and wire 92 thereby producing in the solenoid a magnetic field whose intensity can be regulated (for instance by the time during which the current passes) so that it is greater than that of the field produced by the first branch. Therefore by closing the switch 104 during the operation of the contact making and breaking mechanism 88-89, the more intense field controlled by 104 will cause the movable core 81 to be stopped or held, while at the same time magnetizing the core 80 more strongly. The extent and duration of the movements of the core 81 can be regulated by adjusting the stops 96 and 97 and the counterweight 98. In certain cases, a movable armature 105 can be arranged near the stationary core 80, in order to utilize the magnetization developed there and to make it actuate, either directly by magnetic attraction, or by any other suitable means, the switch 104 in order for example to open said switch after the current has passed for a certain length of time. This armature could in the same way actuate in any suitable manner, the device for closing switch 84. In certain other applications, the stationary core 80 is given a form adapted to enable it to actuate any other desired device, either directly by magnetic attraction or indirectly by any suitable transmission gear. The core may, for example, be provided with heads or projections of any suitable form. One could also cause the switches 84 and 104 to coöperate so as mutually to control their maneuvers under certain conditions. An adjustable stop may be arranged above the movable core 81. One could also arrange, in each branch of the circuit supplying the solenoid, a switch, either actuated or not,

a resistance, any source of current or any other device adapted either to vary the magnetic field of the solenoid by controlling the duration of the period of passage of the current, or in any other manner by controlling the current itself, or adapted to control other organs of the device. The solenoid or electro-magnet can be replaced by any winding or coil capable of creating a magnetic field or of feeding a core or armature.

The transmitting instrument shown comprises a key-board A' and a casing B' which latter has an intermediate partition C', so that a chamber or space D' is formed. The mechanism comprises a magnetic device having a double action, the reciprocating movement of the movable core being utilized to bring the type or printing characters carried by a wheel into printing position, while the attractive movement of the armature of the fixed core serves to effect the impression. The keyboard A' has a suitable number of keys *a* (Fig. 5), each of which is mounted on a vertical lever *b* guided in the upper wall *c* of the keyboard casing and recessed so as to form, on the one hand, a cam *d* adapted to actuate a horizontal frame *e* and, on the other hand, an abutment *f* which is adapted to sink below a second frame *g*. The two frames *e* and *g* are guided in the casing of the keyboard by rollers *h* and are provided with returning springs (not shown) which tend constantly to return them to the position shown in Fig. 5. The frames are perforated to allow the passage of the rods *b*, and these perforations are sufficiently large to permit movement of the keys. Each rod *b* has an extension *i* which serves as a guide to a returning spring *j*, and passes through the bottom A² of the casing A' of the keyboard. A stop *k* made of insulating material is mounted on the lower extremity of the rod above a perforation *m* made in a metal plate *n* insulated from the casing, said perforation being closed by a metal disk *o* held in place by a leaf-spring *p*. Below each of the holes *m* is arranged a contact member *q*, supported in a plate *r* of insulating material and connected by a wire *s* and a metal rod *u* which passes through partition C' to a contact member *v* fitted on the inner face of this partition. These contacts *v* which correspond in number to the keys *a* are arranged in a circle and insulated one from the other, each one being connected in the same way to the various contacts corresponding to the keys *a* of the keyboard. The upper frame *e* is provided at its inner end with a vertical insulated arm *x* carrying a horizontal rod *y* placed opposite a spring contact *z* which is situated near a fixed contact *t* connected to the terminal 11. The movable contact *z* is fastened to a fixed terminal 1 which is connected electrically to plate *n* by a metal strip *w*. A conductor 2 connects terminal 1 to a

metal support 3 (Fig. 7) on the end of which is mounted a fixed contact 4, the position of which can be adjusted by means of thumbscrews 5 and 6. This support rests on a conducting frame 8, an insulator 7 being interposed, said frame being connected on the one hand by a wire 9 to one terminal 10 of a condenser 12 as shown in Fig. 8, which again is connected by terminal 14 placed outside the casing B' with the receiver (not shown); and on the other hand by a wire 15 to the winding of a solenoid 16 (see Fig. 7), the wire 17 leaving the same being connected to a second internal terminal 18 of the condenser as shown also in Fig. 8. The solenoid 16 is fixed to a frame 54 which can slide vertically on the front face 55 of the casing B', and which is attached to the latter by screws 56 (Fig. 9) screwed into the frame and passing through elongated holes 57 in the wall 55, against which their heads bear by means of a plate 58. An adjusting device (not shown) renders it possible to alter the vertical position of frame 54 and of the 25 coil which it carries. The coil comprises two cores, one of which 19 is fixed and the other 20 is movable and pivoted at its upper end to a horizontal shaft 21 which is fixed to a lever 22, pivoted at 23 on the fixed frame 8. This 30 lever is provided at one end with a returning spring 37 having an adjusting screw 38 and carries at its other end a movable contact consisting of a roller 24 supported by an insulating sleeve 25 and connected by a wire 35 26 to a frame 8. The outer end of lever 22 carries a pawl 27 arranged opposite a ratchet wheel 29 keyed on a horizontal shaft 30 which latter is journaled in the walls of the casing B' and pivoted in the center of the 40 circle formed by the contacts *v*. Lever 22 terminates in a fork in which is mounted a pin 33 fixed to two arms 34 and 35 mounted loosely on shaft 30. In the outer face of lever 34 is pivoted a spring-actuated pawl 39 45 which can engage with a ratchet wheel 40 which comprises, like ratchet 29, a number of teeth equal to the number of contacts *v* and in a corresponding position. The teeth of the two ratchet wheels 29 and 40 are arranged in opposite directions and a pawl 41 is provided for ratchet wheel 40. The fixed frame 8 is connected by a conducting brush 42 to the hub 43 of a lever 44 keyed on shaft 30 and insulated therefrom and carrying a 55 brush 45 which contacts with the contact studs *v*.

Near the lower end of the stationary core 19 (Fig. 7) is fitted a movable armature 46 having a returning spring 52, pivoted at 47 and hinged to the lower extremity of a connecting rod 48, the upper end of which carries a crosspiece 66 guided in slides 49, and with which engages a horizontal lever 50, passing through the front wall of casing 60 B' and supporting a printing block 51.

Above the printing block 51 is arranged a type-wheel 53, mounted on an external extension of shaft 30 and comprising characters or signs in number corresponding to those marked on the keys *a* and arranged in a manner corresponding to the contact studs *v* and the teeth of ratchet wheels 29 and 40. The crosspiece 66 which is fixed to the rod 48, carries a pawl 67 in engagement with a ratchet wheel 68 mounted on the axis of a roller 69 for guiding the strip of paper 71, on which bears another spring roller 70 (Figs. 6, 7 and 8). The paper strip is guided by loose rollers 72 and is fed from a drum mounted on a shaft 73 fitted in chamber D'. An inking pad 74 is arranged near the typewheel 53.

The mechanism for releasing the keys is constituted by a bent lever 75 pivoted on a bracket 76 fixed to the front wall 77 of the keyboard, one end 78 of which lever passes through the wall of casing B' and engages the crosspiece 66. The lower end 79 of this lever engages with frame *g*.

The apparatus acts as follows:—If one of the keys is pressed down, for instance, the one bearing letter P, into the position shown in dotted lines in Fig. 5, it will be held in this position by frame *g* and is locked under said frame by its abutment *f*. In the downward movement, cam *d* brings the upper frame *e* into the position shown also in dotted lines, in which position rod *y* presses on the movable contact *z* and brings it into contact with the fixed contact *t* (Fig. 8). The current coming from terminal 11 passes via contact *t*, contact *z*, terminal 1, conductor 2, Fig. 8, support 3, fixed contact 4 Fig. 7, movable contact 24, wire 26, frame 8, and wire 15, and passes through the coil of the solenoid 16 and causes core 20 to be attracted. The latter descends, taking with it lever 22 and the organs supported by it, so that the contact between 4 and 24 is broken and the solenoid is no longer excited. The spring 37 then acts on lever 22 and oscillates it to bring the elements into the position shown in Fig. 7, for both receiving and transmitting instruments. During the oscillating movement of lever 22 caused by the attraction of core 20, the journal 33 is caused to descend, taking with it levers 34 and 35 so that pawl 39 turns ratchet wheel 40 by one tooth. Pawl 27 also comes into engagement with a tooth of wheel 29 and, by reason of the opposite arrangement of the teeth of these two wheels, prevents the whole from turning more than one tooth. The brush 45 then passes from one contact stud *v* to the next, and the type wheel 53 turns also by an amount equal to the distance between two characters. As shown on the diagram, Fig. 14 the same effects are produced in both transmitting and receiving apparatuses, connected to each other by means of a 110

single line wire. On the other hand, on the depression of key *a*, the corresponding metal disk *o* coming into contact with spring-contact *q*, the terminal 1 is connected by plate *w* metal plate *n*, depressed disk *o*, corresponding spring contact *q* and wire *s* to the contact stud *v* corresponding to this key. When in consequence of the partial rotations produced by successive excitement of 10 solenoid 16, the brush 45 arrives opposite contact stud *v* corresponding to the depressed key of letter *P*, the following circuit through the solenoid is closed: terminal 1, plate *w*, plate *n*, disk *o*, spring contact *q*, 15 wire *s*, contact stud *v*-brush 45, hub 43, contact 42, fixed frame 8, wires 15 and 17, so that the magnetic field in the solenoid becomes more intense and causes the movable core 20 to be held in its attracted position; 20 shaft 30 carrying typewheel 53 being locked in position by pawls 27 and 41. The armature 46 of the stationary core 19 is also attracted, rod 48 raises printing block 51, which brings the strip of paper 71 into contact with the letter which is situated at this 25 moment at the lowest point of wheel 53, and corresponding to the key depressed, so that this letter *P* is printed on the paper. During this rising movement of rod 48 and cross 30 piece 66, the end 78 of the bent lever 75 is raised, so that the end 79 of this lever is moved toward the left, taking with it frame *g*, which moves away from projection *f*, so that rod *b* of the key is returned by spring *j* 35 to the position shown in full lines in Fig. 5, while the frames also resume their original position, under the action of returning-springs not shown. The circuit passing through the contact studs *v* is then broken, 40 the magnetization of solenoid 16 ceases and its armature 46 resumes the position of Fig. 5, with rod 48 and the members it actuates, under the action of spring 52. The pawl 67 in descending, turns ratchet wheel 68 by one tooth, and roller 69 advances the paper strip 45 71, by a suitable amount.

This apparatus presents the following advantages: The arrangement of an electromagnetic device, having different actions, 50 for controlling the several parts, enables one to use a single current-conducting wire bringing current from a single source, thereby diminishing the size and cost of the apparatus. The device can be utilized to send 55 cipher messages, by displacing the brush 45 or the type wheel of the receiving instrument by a certain amount relative to that of the transmitting station, the message sent in ordinary language by the transmitting 60 station will be automatically transformed on receipt according to a certain rule. This displacement could also be effected at the transmitting station. The apparatus described permits direct current of constant 65 sign to be used, in distinction from certain

known apparatus which use currents of opposite sign to produce the various movements of their parts.

When utilizing the device described on a telephone line, or on a telegraph line, it may 70 happen that communication between the two stations is cut at the moment when a message is being sent, and that the receiving apparatus alone receives current and continues to act, so that the brushes of transmitting and receiving apparatus become 75 relatively displaced. In order to remedy this drawback, there is provided an apparatus for resetting into concordance. In order to insure the synchronous working of the apparatuses, the latter are arranged in the manner shown by the diagram of Figs. 15 and 15^a. The free end of the lever 22 which supports the movable core 20 of the solenoid 16, is provided with a head 106 80 opposite to two contacts 107 and 108 connected with the (+) and (-) terminals respectively of a source of electric current and from the said lever, insulated from the mass, starts the wire 109 of the line which latter, 85 for each apparatus passes through a relay 110 of any suitable construction, the armature 111 of which is connected with the supply of a local source of electricity and is adapted to bear against a contact 112 connected with the inlet wire 2 of the coil 16, for one direction of the line current. Owing to this arrangement, if the lever 22 of the apparatus placed on the left hand, supposed as being a transmitter in Fig. 15, 90 assumes the position indicated with dotted lines, the head 106 being in engagement with the contact 108 of the source (+), a current in the (+) direction will be sent in the line, said current ending at the (-) terminal of the right hand apparatus and passing through the relays which are energized and brought into their working position, 95 whereby a local current will be sent in each coil 16 of the two apparatuses thus producing the attraction of the two cores which 100 will assume a position symmetric to that indicated by the dotted lines. In this displacement the heads 106 have reached the contacts 107 in consequence of which the 105 line is supplied with a current flowing in the (+) direction, that is to say starting from the (+) terminal placed at the left and ending at the (-) terminal of the left hand apparatus. The direction of the current in the line being thus inverted, the armature 111 of the relays is pushed back in the other direction thus cutting off the supply of current in the wire 2 of the coils, 110 causing the springs of the cores 20 to return the said cores in the position of rest indicated in dotted lines. A current in the (+) direction is thus again sent into the line, the relays produce the attraction of the 115 movable cores, cutting off again the line cir- 120 125 130

cuit and this operation will be continuously renewed.

If the coils of the apparatuses which are connected to each other do not present the same characteristics and if before one of the cores of the coils has a tendency to move more quickly than the other core, the arrangement according to Fig. 15 will secure the synchronous working of the connected apparatuses, for, in order that one of the cores leaves a determinated position it is necessary that the core or the cores of the apparatuses to which the first mentioned core is connected has reached this actual position. For example, if the left hand core in Fig. 15 has a tendency to oscillate more quickly than the right hand apparatus, and if it has been returned to its position of rest symmetric to that indicated by the dotted lines when the core of the right hand apparatus has reached the position indicated in dotted lines, then the (+) current sent through the right hand apparatus in the line is unable to flow through the line because it would end at the (+) terminal of the apparatus placed at the right hand. Thus, no current whatever is circulating in the line and as not any influence changes the position of the relays, the energizing circuit of the right hand solenoid remains completed until the attraction of the core has taken place and until this core has again been returned into its position of rest which is symmetric to that indicated by the dotted lines. It is seen that by this means a perfect synchronous working of the apparatuses is obtained.

A device has also been provided, enabling the apparatuses of being returned to zero or in concordance with each other. On the spindle 30 of the type wheel is keyed a disk 113 the periphery of which has a notch 114 intended to be engaged by a finger piece 115 on a lever 116 pivoted at 117 and having at one of its ends a pivoted pawl 118 which can engage with a ratchet wheel 119 keyed on the spindle 120 of a cam wheel 121 having a number of cams preferably equal to one half of the number of teeth of the ratchet wheel 119. Under the action of a spring 122 a lever 123 is pressed against the cam wheel, the said lever being keyed on the axis 124 of a drum 125 which forms the movable part of a switch and bears two pairs of conducting levers 126, 126' and 127 the pair of contacts 126, 126' pertaining for example to the line circuit, and the pair 127 to the corresponding relays of the apparatus. The levers 126, 126' have their ends placed opposite to the terminals or contacts 128, 129 and 130 arranged in a convenient manner. The spindle 120 passes across the wall of the box and externally to the said box it bears a needle 131 as well as an operating knob 132.

On the cross piece 66 is a stem 133 which

extends laterally above the lever 116. The arrangement of the parts is such, that the notch 114 in the disk 113 assumes the position shown in Fig. 16 when the solenoid has been acted upon by a special key which returns the system to zero. Thus, when the key is depressed, and only at this moment, the notch 114 comes into the position of Fig. 16 and the finger piece 115 engages this notch and assumes the position shown by the said figure. During the normal working, the several parts are in the position of Fig. 18, the finger piece 115 bearing against the periphery of the disk 113 and the pawl 118 being out of engagement with the ratchet wheel 119. If the key for returning the apparatus to zero is depressed, the parts reach the position of Fig. 16, the pawl being then engaged with one tooth of the wheel 119, and when the cross piece 66 is lowered after printing, the stem 133 on the cross bar 66 presses on the left part of the lever 116 and will produce a rotation of the wheel 119 by one tooth. The wheel 121 will therefore turn by half a tooth and the lever 123 which was resting on the bottom of a cam is placed on the projection of this cam, thereby producing an oscillation of the drum around its axis and breaking the contact between the levers 126, 126' and the terminals 128 and 129 respectively to bring them into contact with the terminals 129 and 130. Thus, the corresponding extremity of the line communicates with a pole different from the original one, so that if no change has occurred at the other end of the line, no current can flow through the line because the latter is connected with poles of the same name.

When it is desired to reestablish the concordance between the apparatus from the transmitter, a key of the latter is depressed, whereby a printing is produced in each transmitting and receiving apparatus. At one moment the disk 113 of the receiver will reach the position of Fig. 16. When the cross bar 66 has effected the corresponding printing the stem 133 presses on the end of the lever 116 at the moment where the cross bar is again lowered under the action of the return spring, and this will cause the wheel 121 to turn by half a tooth, whereby the corresponding levers 126/126' will be engaged with another set of contacts. At this moment the two ends of the line are connected with poles of same name so that when the operator again depresses a key of his keyboard he will obtain no passage of the current in the line and consequently no action in the apparatus. By this way he is warned that the receiver is in a determinated position or "zero" position. He brings then the type wheel of his transmitting apparatus into the same position; then, by means of the knob 132 he will reverse the position of 133

the switch 125 of the transmitter and both apparatuses are ready for a concordant working.

The operation is the following: At rest, 5 each apparatus is in a so-called "receiving" position to which corresponds a determinated position of the switch 125, which must be so, that the apparatus is able to receive at any moment a despatch from any 10 transmitter. When any apparatus is desirous to send a despatch the direction of its double switch is reversed whereby the polarity of the end of the line and of the relay is changed, and the despatch can be forwarded without any necessity of specially 15 preparing the receiving apparatus, being understood that the necessary connections have been previously established. When the transmission of the despatch has come to 20 end, the operator returns the switch to the position of rest or receiving position. A despatch could however be received through this apparatus even if the reversal of the poles has not been effected. In this case it 25 would be sufficient that the operator of any other apparatus, acting as a transmitter, by observing that his apparatus is unable to work when connected with the aforesaid receiver, changes the position of his switch to 30 obtain the working of the two apparatuses as may be easily understood. In this case the connection between the terminals and the keys could be changed in any suitable manner to obtain the short-circuiting of the coils 35 16 and the printing by the breaking of the line current.

When the apparatus is to be used solely as a receiver, keyboard A can be suppressed and casing B' retained, doing away with 40 brush 45, contact studs v and trembler contact 4.

The rod 48 connecting armature 46 of the stationary core to the printing device, is provided with a suitable device not shown, 45 for varying its length to adjust it to various positions relative to solenoid 16 and its frame.

The invention is applicable to the transmission of messages or despatches of any 50 kind and in certain cases can be utilized to actuate instruments at a distance. The electro-magnetic device can also be applied to the actuation of apparatus of all kinds, or to the production of electrical, electro-magnetic, or mechanical effects.

Having now particularly described and ascertained the nature of my said invention and in what manner the same is to be performed, I declare that what I claim is:—

60 1. A printing telegraph embodying a keyboard, a movable frame actuated by the keys of said keyboard, a solenoid having a movable core, a rod carried by said frame and controlling one branch of the circuit of the

65 solenoid, a fixed contact in the circuit branch, a source of current for feeding said contact, a contact movable into engagement with said fixed contact, a second fixed contact having connection with said movable contact, a contact carried by the said solenoid core and movable to engage said second fixed contact and also having connection with the solenoid, and a condenser with which the solenoid is connected, all for the purpose described.

75 2. A printing telegraph embodying a magnetic controlling device including a solenoid having a movable core and a lever having connection with said core, and a printing mechanism including a typewheel having a shaft, a pair of arms mounted loosely on the shaft and carrying a journal with which the said lever is connected, a ratchet wheel secured upon the shaft, a pawl carried by one of said arms and engaging said ratchet wheel, a retaining ratchet wheel also secured on the shaft, and a pawl carried by the said lever and adapted to engage said retaining ratchet wheel.

80 3. A printing telegraph, embodying a keyboard, having movable keys, contact members arranged in the path of movement of each of the keys, contact studs with which said contact members have connection, a typewheel around which said studs are arranged, a brush carried by said wheel and movable upon the said studs, a second brush having connection with said first brush, a solenoid having a movable core, and in electrical connection with said second brush, 85 and a condenser also in electrical connection with said second brush.

90 4. A printing telegraph embodying a solenoid, having a movable core and a stationary core, an armature movable toward and away from the stationary core, a rod to which said armature is hinged, a returning spring connected to said rod, a movable cross piece to which said rod is also connected, a typewheel, a printing block mounted below the typewheel, a lever carrying the printing block and having connection with said cross piece, a paper feed roller mounted adjacent said typewheel and printing block, a ratchet wheel having connection with said feed roll, and a pawl carried by said cross-piece and engaging said ratchet wheel.

95 5. A printing telegraph embodying a keyboard having keys, a frame movable by means of the keys and beneath which portions of the keys are adapted to be locked, a solenoid having a stationary core, an armature movable toward and away from said core, a cross piece having connection, and movable, with the said armature, a pivoted angular lever, one arm of which is connected to the said movable frame, and the other arm of which is connected to said cross

piece, whereby attraction of the armature to the solenoid core serves to release a locked key.

6. In a printing telegraph, the combination of a source of current having its terminals provided with spaced contacts, a solenoid having a movable and a stationary core, a lever actuated by the movable core and provided with a contact movable between the said spaced contacts, electrical connections including a relay, a bi-polar

switch controlling the polarity of the relay, an armature movable to and from the said stationary solenoid core, and means actuated by said armature for moving said switch.

15

In testimony whereof I have hereunto placed my hand, this 30th day of December 1911.

B. SOLDATENCOW.
